(57) **CLAIM**

The ornamental design for a bottle opener and stand, as shown and described.

DESCRIPTION

FIG. 1 is a top perspective view of the bottle opener and stand showing our new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a bottom plan view thereof, shown without the stand for convenience;

FIG. 7 is a front elevation view thereof, shown with the stand;

FIG. 8 is a rear elevation view thereof; and,

FIG. 9 is cross-sectional view thereof taken along the line 9-9 in FIG. 8.
